[57] ABSTRACT

A lasting machine for pulling the leather of the upper and turning the rim of the upper over the insole of a shoe disposed on a firmly clamped last, in which a rotating worm extends transversely of the longitudinal direction of the last and rests on the rim of the upper, to draw the latter inwardly and urge it onto the adhesive coated insole. Hydraulic piston and cylinders move the worm longitudinally and transversely of the longitudinal direction of the last substantially parallel to the surface of the sole of the last, and a sensor is guided for movement with the worm and is adapted to sense the edge of the last and actuates a control valve for controlling the application of hydraulic fluid to the piston and cylinder arrangement, to control the pressurization of the latter and, thereby, movement of the worm transversely of the last, as the sensor moves along the edge of the last.

LASTING MACHINE

The invention relates to a machine for pulling the leather of the upper onto and turning the rim of the upper over the insole of a shoe disposed on a firmly clamped last. One type of such machine has a rotating worm extending substantially transversely of the longitudinal direction of the last and resting on the rim of the upper, drawing the latter inwardly and urging it onto the insole provided with an adhesive, and has a sensing device which directs the worm longitudinally of the last in conformity with the contour of the last.

Lasting machines wherein a rotating worm is adapted to be pressed onto the sole surface of the last such that the worm, by virtue of its rotation, draws the upstanding rim of the upper toward the centre of the last, in so doing presses the rim of the upper onto the adhesive coated insole and thereby sticks it fast, have been known for some time (cf, German Patent Specification No. 868,713). However, in these older machines the last and the upper located thereon are manually guided through the machine by an operator, so that adapting the position of the worm to the base and the edge of the last is carried out by the operator himself. In order to be able to automate the operating steps occurring in the manufacture of shoes it has therefore already been proposed for the last provided with the upper to be firmly clamped in a machine. This, however, makes it necessary precisely to guide the tools intended for performing the operating steps depending on the configuration of the last, e.g. depending on the contour and arch of the last. For this purpose sensing devices have been developed wherein a sensor senses a model precisely disposed relative to the last and guides the tool correspondingly (U.S. Pat. No. 3,233,438, German Offenlegungsschriften Nos. 1,685,488 and 1,812,461). The use of models to be sensed again renders questionable any extensive automation of the process of shoe manufacture, because, upon every change-over from left to right shoes or vice versa and upon every change of size or model of shoe, it becomes necessary to replace the model and precisely align it with the last. Furthermore, it frequently happens in shoe manufacture that at the end of a production run pairs of shoes of a certain size or model are found to be rejects and therefore suitable new pairs have to go through the lasting procedure where everything had already been adjusted to a new size or model or both. In such cases too it then always becomes necessary again to replace the model in order to relast the rejected pairs of shoes. The use of the model results in an operator always having to be present to arrange for the correct replacement.

Moreover, the model which must, after all, be present for each size and each model requires costly storage arrangements which are reflected in increasing the total production costs.

According to the present invention, there is provided a lasting machine for pulling the leather of the upper and turning the rim of the upper over the insole of a shoe, such machine comprising means for firmly clamping a last, so that the sole surface of the last extends in a longitudinal direction, a rotatable worm, means for mounting said worm, so that it extends transversely of the longitudinal direction of a last held by said clamping means, and adapted to rest on the rim of a shoe upper positioned on said last and draw the rim inwardly of said last, means for moving said worm lon-

gitudinally of said last, a fluid actuated piston and cylinder arrangement connected to move said worm transversely of the longitudinal direction of said last, substantially parallel to said sole surface, a sensor guided for movement with said worm and adapted to sense the edge of the last; and a control valve for controlling the application of fluid under pressure to said piston and cylinder arrangement, said sensor being operatively associated with said control valve to control the pressurisation of the piston and cylinder arrangement and thereby movement of said worm, as the sensor moves along the edge of said last. With such a machine it is possible so greatly to automate the entire lasting process that a single operator at most is required for the lasting of tip, joint and heel, otherwise the lasting process is entirely automatable.

The piston and cylinder arrangement for adjusting the worm has two functions: on the one hand it ensures the necessary reaction force so as to support the reaction pressure of the worm, which may be considerable, while the worm pulls the edge of the upper over the insole. On the other hand the piston and cylinder arrangement also guides the worm so that it follows the contour of the last. Both functions are effected by the sensor-directed control valve which so regulates the supply of fluid to the two piston surfaces of the advantageously used double acting piston that the piston is advanced or retracted according to the variations in the configuration of the last.

A separate sensing of the arch of the last for the purpose of guiding the worm also perpendicularly of the base of the last is unnecessary since for this purpose there is only required a device for keeping the worm adjustable perpendicularly of the sole surface of the last and to urge it onto the edge of the upper and base of the last with a predetermined force, for example by means of a hydraulic cylinder which is always loaded at constant pressure.

Suitably the piston within the cylinder adjusting the worm parallel to the base and transversely of the longitudinal direction of the last is adapted to be acted upon from either side and the supply of pressure medium is so controlled that the pressure medium supply to one side of the piston which effects the adjustment is interrupted by the control valve when the sensor touches the edge of the last. The adjustment movement is thereby arrested and an oppositely directed force acts on the piston and seeks to remove the piston and thus also the worm away from the last. But when a movement in the opposite sense is initiated then the control valve is again reversed and the piston is instantaneously acted upon by fluid toward the last. By virtue of the inertia of the displaced components in the valve and of the cylinder and by virtue of the throttling and friction effects on the moved components of the valve and the cylinder and those components through which the pressure medium flows a stable condition will, however be established which exactly corresponds to a follow-up control.

The control valve is advantageously a spool valve, the spool of which is directly actuated by the sensor.

The lasting of the arch must be performed in such manner that in the finished shoe the upper forms a so-called "close fit" with the foot in the arch region, i.e. that it smoothly and neatly adheres to the foot. When lasting the arch this requires special care on the part of the operator so as to avoid too much or too little

force being applied to the edge of the upper being lasted on the insole. Since such supervision must be absent when the arch is being lasted automatically provision must be made by a suitable device for the worm to grasp and turn over the rim of the upper in the arch region in such manner as is necessary to obtain the "close fit" in the finished shoe. In order to achieve this there are provided in the arch region, according to a further development of the invention, orienting elements, e.g. temporarily acting pincers, which constrain the edge of the upper toward the inside until it has been gripped by the worm. It is thus ensured that the upper leather is in contact with the edge of the last or the rim of the insole from the very beginning and therefore cannot form bubbles ahead of the worm.

In order that the invention may more readily be understood, the following description is given, merely by way of example, reference being made to the accompanying drawings, in which:

FIG. 1 is a front view, in partial vertical section, of the worm and sensor mounting at one side of the last, including the elements for actuating the worm and the sensor, forming part of one embodiment of machine according to the invention;

FIG. 2 is a plan view of that part of the machine which is illustrated in FIG. 1, the worm mounting and the sensor mounting being shown separately for greater clarity;

FIG. 3 is a side view of the last abutment viewed in the direction of arrow A in FIG. 1;

FIGS. 4a, and 4b are respectively a side view in the direction of arrow A of FIG. 1 of a device for constraining the rim of the upper and a front view of this device;

FIG. 5 is a front view in partial section of a last support and a device for longitudinally orienting the last; and

FIG. 6 is a schematic view of a portion of the hydraulic circuit for controlling the machine.

FIG. 1 shows essentially that part of the machine which serves for mounting and actuating the sensor and the worm. In essence this part comprises a base frame 1 only partially shown, a displacement mounting generally designated by the reference numeral 2, a worm mounting generally designated by the numeral 3 and including a drive, and a sensor mounting generally designated by the numeral 5.

At both lateral surfaces of the box-shaped base frame 1 there is provided a longitudinal guideway 11 extending perpendicularly of the plane of the drawing of FIG. 1 in which guideways a forwardly projecting support arm 12 is displaceably guide. At the free end of the support arm 12 two columns 13 (only one of which is visible in FIG. 1) positioned one behind the other are displaceably guided in guide bushings 14. To each free end of the support arms 12 there is further secured a vertically positioned piston and cylinder arrangement 15 the piston rod 16 of which is adapted to be driven upwardly and connected to the displacement mounting 2. A prestressed spring 17 surrounding the piston rod 16 and carrying the weight of the displacement mounting 2 and of the mountings 3 and 5 is supported between the upper end of the piston and cylinder arrangement 15 and the underside of the displacement mounting 2.

That end of the support arms 12 which is guided in the longitudinal guideway 11 is in each case connected to one end of a crosshead 18 which is adapted to be ad-

vanced and retracted by means of a hydraulic cylinder (not shown) disposed in the base frame 1. Thus the two support arms 12 and with them the mountings 2, 3 and 5 can be jointly shifted perpendicularly of the plane of the drawing of FIG. 1.

A guide bed 21 is secured to the upper extremities of the columns 13 and a hydraulic cylinder 23 is disposed at the righthand (in the Figure) end of the guide bed by means of an angle member 22. The piston rod 24 of the hydraulic cylinder 23 is connected to a sliding carriage 25 displaceable in a rectangular or dovetail groove which extends parallel to the plane of FIG. 1 for example. The piston of the hydraulic cylinder 23 is adapted to be acted upon, in a manner yet to be explained in greater detail; from either side by virtue of connections 26 and 27, so that the sliding carriage 25 can be moved to the left or to the right.

The sliding carriage 25 carries a mounting plate 28 to which the worm mounting 3 is attached. The latter comprises essentially an approximately horizontally positioned cylindrical housing 31 having at either end cavities 32 and 33 for receiving roller bearings 34 and carrying a hydraulic motor 35. The drive shaft of the hydraulic motor 35 acts directly on the worm shaft 36 journalled in the roller bearings 34 and drives, via the worm shaft 36, a worm roll 37 mounted at the leading end of the drive shaft, so as to be pivotable in any direction. The worm roll 37 has a single or multiple helical thread the outer edges of which are slightly rounded. At its end proximate the mounting the worm roll 37 has an articulation ball 38 borne in a socket 39 of a cap-nut-like sleeve 40 threaded onto the worm shaft 36. The ball 38 has at its free end a planar thrust surface 41 positioned perpendicular to the axis of the worm, against which surface 41 the likewise planar face of an offset thrust pin 42 is urged by a set of prestressed cup springs 43. In this manner the worm roll 37 can only be swivelled transversely of its longitudinal axis to the extent to which the bias of the cup springs 43 allows. This kind of mounting of the worm roll 37 makes possible adaptation to the laterally sloping edge of the last L which is of special importance at the inner side of the arch. Transmission of the torque from the worm shaft 36 to the articulation ball 38 is effected via an entrainment pin 44 diametrically passing through the ball 38, both ends of which pin project beyond the ball 38 and protrude into bores 45 of the sleeve 40. The size of the bores 45 is such that they permit pivoting of the worm rolls 37 to the extent to which this is required. By threaded moving the sleeve 40 inwardly or outwardly on the worm shaft 36 the cup springs are more or less severely prestressed. The sleeve 40 is locked by a lock nut 46.

As is apparent from FIG. 2 the longitudinal axis of the worm roll 37 is not positioned perpendicular to the median plane of the last L but is inclined toward the heel of the last at an angle of about 5° relative to the perpendicular. It has proved that with this arrangement the worm roll 37 correctly lasts the rim of the upper over the edge of the insole without an angular setting relative to the edge of the last being required.

At that face of the bearing housing 31 which faces the last L, there is secured a swivel bearing fork 51 (FIG. 1) wherein a guide means 53 is mounted, by means of a pivot pin 52, so as to be pivotable about an axis perpendicular to the plane of the drawing of FIG. 1. The guide means 53 consist of two parallel rails 54

(FIG. 2) forming a contact and slide surface for a sliding carriage 55 having an attachment 56 projecting downwardly between the two rails 54. The sliding carriage 55 further has a longitudinal groove 57 wherein a flat rod 58 is secured. Finally, a control valve 59 is rigidly connected to the guide means 53, the gate spool of which is spring biased toward the left (in FIG. 1) and the free end 60 of which spool contacts an abutment angle member 61 firmly connected to the flat rod 58.

At its free end the flat rod 58 has a downwardly directed arm 62 which is led laterally past the worm roll 37 and is then bent inwardly under the worm roll 37 to a roll carrier 63 in such manner that the axis of a sensing roll 64 is situated substantially vertically below the axis of the worm roll. The sensing roll 64 is upwardly conically bevelled such that the point of contact with the upper drawn over the last L is situated as close to the periphery of the worm roll 37 as possible.

To the attachment 56 projecting downwardly between the guide rails 54 there is connected the end of a piston rod 65 of a double-acting piston and cylinder arrangement 66 by means of which the sliding carriage 55 can be moved, between the guide rails 54, towards or away from the last L. A roller 67 of the attachment 56 thereby rolls over the upper surface of the housing 31. In the path of movement of the roll 67 there is disposed a curved element 68 which, when the roll 67 runs onto it, causes the entire sensor mounting 5 to swing about the pivot pin 52 so that the sensing roll is lowered out of the range of the sleeve 40 and is not damaged during withdrawal.

The connection principle of the control valve 59 with respect to the hydraulic cylinder 23 for moving the sensor and the worm toward the last L is apparent from FIG. 6. It can there be seen that pressure medium is directly introduced by a pump P via the connection 26 of the hydraulic cylinder 23, while the pressure medium to the connection 27 flows via the control valve 59 and a throttle D. The arrow placed next to the hydraulic cylinder 23 in FIG. 6 indicates the direction toward the last L. Of course, the circuit shown in FIG. 6 represents only the connection principle and other circuit elements are actually provided which are of no importance in this context, and that, for the rest, this circuit is only a portion of the overall circuitry of the lasting machine.

FIGS. 3 and 5 show those elements of the lasting machine according to the invention which prior to performing the lasting process serve to position the last with the upper arranged thereon. FIG. 3 again shows the side view of the base frame 1 of the machine the lateral surface whereof, now lying in the plane of the drawing, shows the slit guidance of the cross head 18. To the upper surface of the base frame 1 there is secured a swivel mounting pedestal 301 in which an angle arm 303 of a swivel arm 304 serving as a last abutment is mounted on a mounting pin 302. The angle arm 303 has at its front a protuberance 305 which cooperates with an adjustable stop screw 306 in the swivel mounting block 301. Approximately half way along the swivel arm 304 and at the underside thereof a thrust member 307 is disposed so as to be pivotable about an axis parallel to the mounting pin 302. The thrust member 307 is of the configuration of a substantial triangular plate mounted close to its apex by means of a pin 308 between two cheeks 309 and having cylindrically rounded

protuberances 310 at either of its lower corners. The cheeks 309 are welded to a slideable member 311 which is adapted to be adjusted in a slot 312 of the swivel arm 304 longitudinally thereof and can be secured in position by means of an eccentric 313. In the region of its free end the swivel arm 304 further carries an abutment roll 314 of adjustable spacing relative to the swivel arm 304. An eye 315 is formed at the rear end of the swivel arm 304 into which the end of piston rod 316 of a piston and cylinder arrangement, not shown in great detail, engages.

A toe presser generally designated by the reference numeral 320 is mounted so as to be pivotable in the plane of the drawing about a pivot bearing, not shown, in front of the base frame 1. The toe presser 320 comprises a body 321 in the form of a cylinder in which a piston 322 adapted to be acted upon from either side is vertically displaceable. The piston rod 323, projecting upwardly from the body 321 has at its upper end a pressure cushion 324 of resilient material which comes into contact with the toe of the last, from below.

A length abutment strip 325 is rigidly secured to that side of the body 321 which faces the base frame 1 and a terminal switch 326 is arranged at the upper end of the strip 325. The terminal switch 326 is in the form of a microswitch and carries a switch pin 327 in front of which a leaf spring 328 is disposed in a manner apparent from FIG. 3.

Downwardly of the point where the length abutment strip 325 is secured, a slot 329 is formed in the body 321 into which slot engages a piston rod 330 which is part of a piston and cylinder arrangement 331 mounted in the base frame 1.

To the front of the body 321 there is secured a further piston and cylinder arrangement, not shown in detail, the piston rod 501 (FIG. 5) of which acts via a pin 502 on the two ends of a pair of links 503 jointly pivotably mounted to the pin 502. The other ends of the links 503 are articulated to the respective end of downwardly projecting angle arms 504 forming the extension of two gripping means 505 disposed on either side of the last L and pivotable in the plane of the drawing. The gripping means 505 are mounted on the shaft 321 in pivot bearings 506.

Resilient pressure cushions 506' adapted to be pivoted in the plane of FIG. 5 about a pin 509 and against the action of compression springs 508 are secured to the upper ends of the gripping means 505 in pivot brackets 507. This arrangement and the configuration of the pressure cushions 506' which can be seen in FIG. 5 serves for adaptation to the lateral surface of the last L.

It is apparent from FIGS. 4a, and 4b that guide grooves 401, extending longitudinally of the pivot arm 304 (FIG. 3), are formed in either longitudinal side of the arm 304, into which grooves engage sliders 402 of a bearer 403 for "arch" pincers or clamping means, which bearer 403 is displaceable on the upper surface of the swivel arm 304. The displacement is effected by a piston and cylinder arrangement 405 likewise secured to the upper surface of the swivel arm 304, the piston rod 404 of the piston and cylinder arrangement engaging the pincer bearer 403. The pincer bearer 403 is itself formed as a cylinder for a piston 406, the upwardly drivable piston rod 407 of which carries a cross head 408 at its upper end. To the two outer ends of the cross head 408 there are hinged pincer shanks 409 pivotable

in the plane of the drawing. The pincer shanks 409 are also designed as cylinders for pistons 410, the piston rods 411 of which are adapted to be driven downwardly and act with their spherical ends on the movable jaws of arch pincers 412. The arch pincers 412 are each held open by a helical spring 413 when the pistons 410 are in their at rest position.

The shafts of the arch pincers or clamps have two bores (not shown) extending parallel to the pivot axis of the pincer shafts 409 located in the vicinity of the points 414 and wherein the terminals of a piston and cylinder arrangement, not shown in detail, are mounted. This piston and cylinder arrangement serves to pivot the shafts of the arch pincers about the mounting in the cross head 408. The maximum angle of pivoting or opening of the pincer shafts relative to one another can be set by means of stop screws 415 contacting the cross head 408.

The manner and sequence of operations of the machine are as follows:

In terms of time the sequence of the individual operations of the machine is dependent on a control programme whereby the hydraulic cylinders of the individual tools and devices are pressurised by pressure medium in a predetermined order. Programmed control arrangements of this kind are adequately known in the appropriate technology and, therefore, need not be explained in detail herein.

A last L is fitted manually, but suitably alternatively automatically by a delivery device, on the mandrel of the last support, such that its toe points approximately toward the rear. The piston and cylinder arrangement associated with the swivel arm 304 is now actuated so that the piston rod 316 moves out and swings the swivel arm 304 into the horizontal. Both the abutment roll 314 and the pressure element 307 are thereby caused to engage the base of the last and so orient the last L relative to the horizontal that the vertical difference between the base of the last and this horizontal remains as small as possible. The lasting tool thereby needs to perform only a short vertical movement during the following lasting procedure.

By virtue of the abutment roll 314 and the pressure element 307 the last is precisely orientated in the vertical direction and constrained. Now the piston rod 501 moves out and pivots the gripper arms 505 simultaneously and steadily toward each other so that they grasp the last L between them and orient it precisely in the longitudinal direction of the lasting machine. Thus the last is laterally fixed by the gripper arms 505 since the links 503 develop a bell crank effect and consequently act very powerfully on the angle arms 504. However, the pressure cushions 506 ensure that damage to the leather of the upper is precluded.

The final fixing of the last L now results from actuation of the toe presser 320. The latter is moved forwardly from an originally pivoted back position, by the movement of the piston rod 330 out of the piston and cylinder arrangement 331, until the leaf spring 328 contacts the toe of the last and the switching pin 327 of the terminal switch 326 is depressed. The signal thus given not only causes the movement of the toe presser to be arrested but it also provides a measure of the pivotal travel performed by the toe presser 20. This measure which can be derived, for example at the piston rod 330, by known means suitably determines, in the succeeding processing stages, the initial position of the

arch pincer arrangement (FIG. 4a) and of the sensor and the worm (FIGS. 1, 2), since their piston and cylinder arrangement 405 and the cross head 18 in the base frame 1, respectively, are brought into a starting position corresponding to the pivotal travel of the toe presser 320.

After the toe presser 320 has been arrested in the position of pivoting determined by the terminal switch 326, the piston rod 323 of the toe presser is driven out so that the pressure cushion 324 disposed at the upper end of the piston rod strongly thrusts from below against the last L and thus clamps the last against the pressure element 307.

When the above described processes have been performed the positioning of the last L in the lasting machine is terminated.

It has been explained above that by virtue of the pivoting movement of the toe presser 320 the arch pincer arrangement (FIGS. 4a, b) and the sensor and worm mounting (FIGS. 1, 2) have also been driven into the correct starting positions. This starting position is determined such that the worm is spaced for example 80 mm from the toe of the last (in direction toward the heel of the last) and the arch pincers are offset yet a further distance toward the heel of the last. This ensures that even with differing sizes the rim of the upper will, after toe lasting, be gripped at the correct point and that the arch pincers will also grip the rim of the upper in the arch at a point where this is of greatest importance.

The arrangement of arch pincers (FIGS. 4a, b) becomes operative first. To this end the piston 406 which is situated at the top in the starting position is acted upon by pressure medium from above in the pincer bearing 403 so that the pincer shafts 409 are driven downwardly until the fixed jaws of the arch pincers 412 stand on the base of the last and the movement is thereby arrested. The pincer shafts 409 are then under the influence of the piston and cylinder arrangement 405 engaging at the points 414, in the closed position shown in FIG. 4b. During this lowering movement the arch pincers are held in the open position by the springs 413 since the cylinders in the pincer shafts 409 remain without pressure. Controlled by the downward movement being arrested, the piston and cylinder arrangement engaging at the points 414 is now actuated whereby the pincer shafts 409 are swung apart and thus the fixed jaws of the arch pincers 412 are guided along the base of the last. If at that time the rim of the upper adheres to the insole, which would affect the following arch lasting process very detrimentally as to operation, then the rim of the upper is now gripped by the fixed jaws of the articulated pincers 412, raised and entrained in outward direction. The outer terminal position of the arch pincers 412 is determined by the stop screws 415 impinging on the cross head 408. Again controlled by the interruption of the spreading movement of the pincer shafts 409 the pincer jaws of the pincers 412 now close as a result of the pistons 410 in the pincer shafts 409 being pressurised. Subsequently the arch pincers 412 again move inwardly as a result of appropriate actuation of the piston and cylinder arrangement engaging at the points 414. It should be emphasized that the arch pincers 412 do not exert a traction on the upper leather comparable to a lasting process, but they only hold the rim of the upper fast and erect, so that the upper adheres satisfactorily to the last and insole edge

in the arch. Thus firm gripping of the edge of the upper by the worms is ensured in the subsequent lasting process. During the lasting process the pincers do not move in the longitudinal direction, i.e. the piston rod 404 of the piston and cylinder arrangement 405 remains at rest. When the above described processes of movement have been completed the last is ready for the actual lasting process.

Simultaneously with the renewed approach of the arch pincers 412 the hydraulic motors 35 are switched on so that the worm rolls 37 rotate. By supplying pressure medium via the connection 27 to the hydraulic cylinder 23, the sliding carriage 25 is shifted toward the last L. The stroke is in this case so adjusted that the rolls do not collide in the median portion of the last. Pressurising the piston and cylinder arrangement 15 by pressure medium causes the piston rod 16 to descend, against the action of the spring 17, and to deposit the worm screws 37 on the base of the last with a specific force, e.g. 50 kp. The compression force of the spring 17 is appreciably greater than the actual weight of the displacement guide means 2 and the mountings 4, 5, so as to be able to supply the piston and cylinder arrangement 15 at high pressure. The installation pressure of e.g. 50 kp can be maintained constant by means of a pressure regulating valve in the feed line to the piston and cylinder arrangement 15 so that the worm roll 37 can on the one hand follow the arch of the last L and on the other hand always exerts an inwardly directed even traction effect on the rim of the upper.

Immediately after the approach movement of the worm rolls 37 toward the median portion of the last the sliding carriage 55 is also driven out by means of the piston rod 65 so that the sensing rolls 64 move to contact the edge of the last. As a rule conditions will be such that at this moment the worm rolls 37 will be located too far in the middle of the last, so that the sensing rolls 64, which are urged against the last by the cylinder 66, with a pressure of, for example, 1 kp, will be arrested in a position in which the abutment angle member 61 of the flat bar 58 depresses the spool end 60 of the control valve 59, to such an extent that the control opening of the spool blocks the supply of pressure medium to the connection 27 of the hydraulic cylinder 23. Thus, only the hydraulic pressure in the connection 26 remains effective so that the sliding carriage 25 and with it the entire worm and sensor mounting including the control valve 59 are moved back from the last L. However, under the influence of the piston rod 65 the flat bar 58 continues to be urged toward the last L so that the sensing roll 64 continually adheres to the last with the aforesaid pressure of 1 kp. The withdrawal of the sliding carriage 25 continues until the abutment angle member 61 has freed the end of the spring loaded gate of the control valve 59, to such an extent that the edge of the control opening of the gate restores supply of pressure medium to the connection 27 of the hydraulic piston 23. In this operating position the piston of the hydraulic cylinder 23 is subjected to a medium pressure corresponding to a force of about 300 kp exerted by the piston rod.

Now the piston and cylinder arrangement disposed in the base frame 1 is pressurised so that the cross head 18 is advanced in the slit guideway of the base frame 1 and via the support arms 12 guides the displacement guide 2 and the worm and sensor mounting 3, 5 longitudinally of the last. During this longitudinal movement

the sensing rolls 64 precisely follow the contour of the last since they are continually urged against the last at a pressure of 1 kp. On the other hand, the abutment angle member 61 continually exerts pressure on the spring loaded spool of the control valve 59 and thus controls the supply of hydraulic medium to the hydraulic cylinder 23 in such manner that the worm rolls 37 always pursue the same course as the sensing rolls 64. If, for example, in the region of the arch the flat bar 58 is driven out farther by the piston rod 65, since in this region the sensing rolls 64 approach the middle of the last in accordance with the contour of the last, then the abutment angle member 61 moves away from the spool end 60, so that the control opening of the spool permits increased supply of pressure medium to the connection 27 and pressure medium is fed into the hydraulic cylinder 23 whereby the sliding carriage 25 follows up. This following up movement is instantaneously interrupted when the abutment angle member 61 again depresses the spool of the control valve 59 to such an extent that the inflow of pressure medium to the connection 27 is interrupted via the control opening of the spool. Without inflow of pressure medium the hydraulic pressure then bears on the piston of the hydraulic cylinder 23 which delivers 300 kp holding power.

When the worm rolls 37 of the arch pincer arrangement (FIGS. 4a, b) have approached to a specific extent, then the pincers 412 release the rim of the upper and move upwardly and, under the influence of the piston and cylinder arrangement 405, to the end of the pivot arm 304. Further constraining of the rim of the upper by the arch pincers 412 is unnecessary for the remainder of the lasting process. This releasing process could be triggered by a terminal switch. However, advantageously the longitudinal movement of the worm rolls 37, i.e. of the cross head 18 in the base frame 1, is sensed, for example by means of a potentiometer, and after travelling over a certain distance determined in relation to the position of the arch pincers the signal mentioned is triggered. This circuitry assists automation of the entire lasting procedure in as much as in contrast to the positioning of a terminal switch which would have to be adjusted at the machine itself for various models and sizes, it permits remote controlled adjustment of the process for releasing the arch pincers.

This situation is established until the worm rolls 37 have travelled their permissible distance, i.e. when the arch lasting process is completed. From this point onwards the above described processes of movement occur in reversed sequence, i.e. the sensors move apart, the hydraulic motors 35 are disconnected, the toe presser 320 releases the toe of the last and pivots back to the starting position, the grippers 505 open, the worm rolls 37 return to the starting position and the pivot arm 304 swings upwardly. The last support may optionally be designed so that it can be lowered and pivoted forward so as to enable an automatic withdrawal device to remove the last and to feed it to a heel lasting machine. A fresh last L can now be positioned on the last support, it being immaterial for the next cycle of the operations described of what size and shape the new last is, since the arrangement and mode of operating described is automatically controlled in dependence on the shape of the last without supervision by an operator being required or a pattern having to be replaced, as had hitherto been the case.

I claim:

1. A lasting machine for pulling the leather of the upper and turning the rim of the upper over the insole of a shoe, said machine comprising, in combination:
  - a. means for firmly clamping a last, having a sole surface, so that said surface extends in a longitudinal direction;
  - b. a rotatable worm;
  - c. means for mounting said worm, so that it extends transversely of the longitudinal direction of a last held by said clamping means, and adapted to rest on the rim of a shoe upper positioned on said last and draw the rim inwardly of said last;
  - d. means for moving said worm longitudinally of said last;
  - e. a fluid actuated piston and cylinder arrangement connected to move said worm transversely of the longitudinal direction of said last, substantially parallel to said sole surface;
  - f. a sensor guided for movement with said worm and adapted to sense the edge of the last; and
  - g. a control valve for controlling the application of fluid under pressure to said piston and cylinder arrangement, said sensor being operatively associated with said control valve effective to control the pressurisation of the piston and cylinder arrangement and thereby movement of said worm, as the sensor moves along the edge of said last.
2. A lasting machine as claimed in claim 1, wherein said piston and cylinder arrangement is double-acting, effective to move the worm towards and away from the last, whereby, when the sensor touches the edge of the last, the control valve acts to cut off the supply of fluid to that side of the piston which causes movement towards the last.
3. A lasting machine as claimed in claim 1, and further comprising a spring to urge the piston of said piston and cylinder arrangement in one direction, fluid pressure urging the piston in the other direction.
4. A lasting machine as claimed in claim 1, wherein the fluid supply to the piston and cylinder arrangement is interruptable by said control valve.
5. A lasting machine as claimed in claim 1, wherein

said control valve is a spool valve, the spool of which is directly actuated by said sensor.

6. A lasting machine as claimed in claim 1, and further comprising a crosshead guide movable parallel to the longitudinal direction of the last, said sensor and worm being mounted on said crosshead guide.

7. A lasting machine as claimed in claim 1, and further comprising a second fluid actuated piston and cylinder arrangement for actuating said sensor.

8. A lasting machine as claimed in claim 7, wherein the piston of said second fluid actuated piston and cylinder arrangement is adjustable.

9. A lasting machine as claimed in claim 1, wherein said sensor is designed as an angled arm, having a sensing end reaching approximately under said worm.

10. A lasting machine as claimed in claim 1 and further comprising a sensing roller mounted on said sensor for contact with said last.

11. A lasting machine as claimed in claim 1, and further comprising an additional fluid actuated piston and cylinder arrangement adapted to move said worm and sensor substantially perpendicular to said sole surface.

12. A lasting machine as claimed in claim 11, and further comprising a spring supporting the weight of said worm and sensor and the mounting means therefor, so that the force of said worm and sensor on said sole surface is determined solely by said additional fluid actuated piston and cylinder arrangement.

13. A lasting machine as claimed in claim 12, wherein the force of said spring considerably exceeds the weight of the worm and sensor and mounting means therefor.

14. A lasting machine as claimed in claim 1, and further comprising means for tilting the last perpendicular to the sole surface of the last effective to adapt the worm to the edge of the last.

15. A lasting machine as claimed in claim 14, and further comprising an articulation ball secured to one end of the worm, a land formed on said ball perpendicular to the worm axis, and prestressed compression springs acting on said land, to constrain tilting of said worm.
